UNITED STATES PATENT OFFICE

WALTER B. CLIFFORD, OF CAMBRIDGE, MASSACHUSETTS, ASSIGNOR TO CLIFFORD MANUFACTURING CO., OF BOSTON, MASSACHUSETTS, A CORPORATION OF DELAWARE

WATER CONTROL

Application filed November 23, 1926. Serial No. 150,368.

The present invention relates to improvements in temperature controlled apparatus for employment in the cooling circulation of internal combustion motors. One object of the invention is to improve and simplify apparatus of this character in a manner to afford the least interference to the flow of water therethrough, and to provide a unit which may be constructed and assembled with a minimum of ease.

A further object of the present invention is to provide a construction of this type, in which the opening temperature and travel of the valve, in moving from closed to full open position, may be duplicated in production without introducing variable factors, due to variations in the character of the bellows, filling medium, etc.

With this and other objects in view, the various features of the invention consists in certain novel features of construction, combinations and arrangements of parts herein-after described and claimed, the advantages of which will be obvious to those skilled in the art from the following description.

In the accompanying drawings illustrating the preferred form of the invention,

Fig. 1 represents an elevation partly in section of the improved water control; and

Fig. 2 is a top plan view of the apparatus shown in Fig. 1.

The apparatus shown in the illustrated embodiment of the invention comprises essentially an open skeleton frame consisting of rods disposed at uniform intervals in the general outline of a cage, and bellows rigidly connected at one end to the skeleton support and having a valve connected to its opposite free end. The valve cooperates with a seat formed upon a disk, which in turn is rigidly locked to the rods of the skeleton support intermediate their ends. As indicated more particularly in the drawing, the skeleton support comprises a series of longitudinal ribs 10 (four in number) disposed at uniform intervals at the corners of a square. Each two of these ribs is formed by a bent rod, preferably of brass or similar material, which, as indicated more particularly in Fig. 1, is bent to form a generally U-shaped member having inward-

ly extending portions or shoulders 12 and upwardly inclined portions 14 terminating in a crown portion 16. The opposite legs of the U-shaped member form the enclosing ribs 10. The complementary U-shaped member, indicated in section in Fig. 1, is slightly modified in form from the member shown in plan. The complementary member is provided with the portions 12 and 14, but the portion forming the crown 16 is depressed at 18 to interlock with the crown portion 16 and rigidly brace the two members when in assembled position against lateral movement. The legs or ribs 10 at their lower ends are connected to a flat disk 20 which is interlocked with the end of a metallic bellows 22. This interlocking of the disk with the bellows is accomplished in the formation of the bellows, the latter being bulged outwardly at 24 to form a locking fold, which in conjunction with the bellows fold 25 rigidly locks the disk to the bellows themselves. The disk adjacent its outer margin is staked to each one of the ribs 10 by oppositely disposed tongues 28 and 29 formed integrally with the rods, as indicated. The upper free end of the bellows in the usual manner is provided with a stem 30 carrying a flat valve 32 which has an integral hub 34 threaded to cooperate with the threaded portion 36 of the stem and permit adjustment of the valve lengthwise of the stem to secure the proper opening temperature of the valve after assembly of the latter in the cage. The valve may preferably be locked in adjusted position on the stem in any desired manner, as by locking nut 38, which in addition may be secured by soldering to the stem. The disk valve 32 seats upon a raised flange 40 formed integral with a partition member 42 which, as indicated, is supported upon the rods 10 intermediate opposite ends of the cage and staked thereto by tongues 44. With this construction, a rise in the water temperature causes expansion of the bellows, due to the vaporizable liquid contained therein, and elevates the valve from its seat. The opening movements of the valve and expansion of the bellows are limited by engagement of the upper face of the valve with the shoulder portions 12 formed upon

the rods. Furthermore, the vertical portions of the rods just below the shoulders 12 form a loose guide to prevent too great deviation of the valve from a straight-line movement. 5 It will be observed that with this form of construction, a minimum of interference is presented to the water way when the valve is completely open, the water flowing freely through the space surrounding the rods both 10 above and below the partition member 42. In the particular embodiment of the invention shown in the drawing, a partition is designed to clamp between the flanges of an enclosing head and be bolted in position through the 15 provision of bolt-holes 50.

It will be evident that this construction may be simply and inexpensively constructed and assembled, as the valve, partition member and supporting disk 20 are simply stampings and the two U-shaped members may be 20 developed by forming dies. Thereafter the several parts are readily assembled by thrusting the two U-shaped members through the partition disk and supporting disk, staking 25 the disks and members together so that the disks occupy a predetermined position lengthwise of the members and cage formed thereby.

It will be furthermore evident that with this construction a predetermined opening 30 temperature of the valve may be obtained independently if minor variations in the bellows and the cage assembly. To this end the valve is loosely threaded upon the stem 30 with the cage assembled thereabout, and the 35 bellows elevated to the desired opening temperature. Thereupon the valve is adjusted on the stem until it is separated from the seat by the requisite or desired amount. Subsequent to this lengthwise adjustment of the 40 valve on the stem, it may be locked in position through the locking nut, solder, or other convenient expedient. It will be evident, therefore, that although the position of the valve upon the stem 30 may vary in order to secure 45 a fixed opening point independent of variations in the bellows, this adjustment of the valve will not in any event vary the travel of the valve between the seat 40 and the overhead stops 12. It will be furthermore evident that with this construction the valve is 50 readily accessible for adjustment, and in full open position the pressure of the valve against the stops places the rods 10 in tension.

55 What I claim is:

1. Temperature-controlled apparatus comprising a generally U-shaped frame formed from a rod, metallic bellows rigidly connected with the frame adjacent one end, a partition connected with the legs of the U-shaped frame adjacent the opposite end, a valve connected with the bellows, and shoulders formed upon the frame beyond the valve designed to limit the movement of the valve away from 60 the partition upon expansion of the bellows.

2. Temperature-controlled apparatus comprising a rod having a generally U-shaped form adapted to act as a limiting stop at the closed portion thereof, metallic bellows rigidly connected to the opposite open end of the U-shaped rod, a partition member having a valve opening connected with the legs of the rod in proximity to the closed portion, and a valve connected to the bellows to control flow through the opening. 70

3. Temperature-controlled apparatus comprising a plurality of U-shaped frames disposed angularly with relation to one another, means for causing the frames to interlock at the closed portions, a partition rigidly connected to the legs of the frame in proximity to the closed portions, metallic bellows rigidly connected to the legs of the frames at the opposite ends, and a valve connected to the bellows and limited in movement by contact with the closed portions of the U-shaped frames. 75

4. Temperature-controlled apparatus comprising a metallic bellows, a stem projecting from one end of the bellows, a disk valve connected to the stem, a supporting member rigidly locked to the opposite end of the bellows, a series of supporting rods extending lengthwise of the bellows rigidly connected at one end to the support, a partition member rigidly connected to the rods adjacent the opposite end having a valve opening formed therein, and limiting stops formed upon the rods designed to limit the movement of the valve away from the opening. 90

5. Temperature-controlled apparatus comprising a metallic bellows, a supporting cage rigidly connected with one end of the bellows, a partition member having a valve opening provided at the opposite end of the cage, a valve adjustably connected with the free end of the bellows and closing the opening, and means for predetermining the full open position of the valve unaffected by the adjustment of the valve relative to the stem. 100

6. Temperature-controlled apparatus comprising a supporting cage, a bellows fixedly connected to the cage at one end, a partition having a valve opening fixedly connected to the cage at the opposite free end of the bellows, a stem projecting from the free end of the bellows, a valve adjustably mounted on the stem, and a stop located at a predetermined distance beyond the valve opening and serving to predetermine the travel of the valve between closed and full open position. 115

7. Temperature-controlled apparatus comprising an open cage, a bellows connected to the cage at one end, a valve seat surrounding an opening at the opposite end of the cage, a stem projecting from the free end of the bellows, a valve mounted upon the stem and adjustable lengthwise thereon for predetermining the temperature operative to actuate the valve, a stop positioned beyond 125

the valve seat and at a predetermined distance therefrom to gauge the travel of the valve from closed to full open position independently of variations in the adjustment 5 of the valve lengthwise of the stem.

8. Temperature-controlled apparatus comprising a cage, a bellows connected to the cage at one end, a valve seat surrounding an opening adjacent the opposite end of the cage, a valve connected to the free end of the bellows and movable therewith, a rod projecting from the cage beyond the valve seat and having a stop portion in contact with the valve to determine the full open position. 10

9. Temperature-controlled apparatus adaptable for circulatory systems of motor vehicles comprising a metallic bellows, a supporting cage rigidly connected with one end of the bellows, a partition member adapted 15 to be secured between the adjacent edges of the water circulating conduits and having an opening shaped to constitute a valve seat, a disk valve adjustably connected with the free end of the bellows for closing the opening upon a contraction of the bellows and removing the valve from its seat upon an expansion of the bellows, and a stop means engageable with the valve and operable to determine the full open position of the valve. 20

10. A device of the class described comprising, a circular plate having an opening therethrough, a plurality of rods passing through the plate and permanently secured thereto, said rods extending at each end beyond the sides of the plate, a charged corrugated metal bellows connected to the rods at one end and lying between the same, a stem extending from the opposite end of the bellows through the opening in said plate, 25 and a valve attached to the end of the stem at the side of the plate opposite where the bellows is located, said valve in one position closing the opening through said plate and in its movements toward and away from the plate being guided by said rods. 30

11. A construction of the class described comprising, a plate having an opening therethrough, a plurality of rods passing through 35 the plate outside of the opening and permanently secured to the plate, said rods extending to each side of said plate, a thermostatically expansible and contractible element located between the rods at one side of the plate and attached at one end to said rods, a stem attached to the opposite end of said element passing through the opening in the plate, a valve secured to the stem at the side of the plate opposite that at which the element is located, said valve being larger 40 than the opening through the plate and closing said opening when in one position, and means extending across the said rods located at the same side of the plate with the valve 45 against which the valve engages on its move-

ment away from said opening a predetermined distance.

12. In a construction of the class described, a plate having an opening therethrough, a pair of U-shaped members having the legs of the U extending through the plate outside of said opening and permanently secured to said plate with the connecting cross members of the U-shaped members located a distance from said plate, a thermostatically expansible and contractible element located between the legs of said U-shaped members and connected at one end thereto, a stem extending from the opposite end of said element through the opening in the plate, a valve secured to the stem at the opposite side of the plate and at the same side as the cross members of the U-shaped members, said valve being guided in its movement by said U-shaped members and limited in its outward movement by said cross members. 70

13. A construction of the class described comprising, a plate having an opening therethrough, a plurality of rods connected to said plate and extending on opposite sides thereof, a thermostatically expansible and contractible corrugated metal bellows located between said rods at one side of the plate and attached at one end thereto, a stem extending from the opposite end of the bellows through the opening in said plate, and a valve secured to the end of the stem on the opposite side of the plate and guided in its movements by the rods projecting from said opposite side of the plate. 80

14. A construction containing the elements in combination defined in claim 13, combined with means located a distance outward from the plate against which the valve engages to limit the movement of the valve away from the plate. 90

15. A device of the class described comprising, a plate having an opening therethrough, a valve to close the opening, a stem to which said valve is connected, a charged corrugated metal bellows to one end of which the stem is connected, means for anchoring the opposite end of the bellows with respect to the plate, and a plurality of rods attached to said plate and lying alongside of said valve to guide the same in its movements as the bellows expands. 100

16. A construction containing the elements in combination defined in claim 15, combined with means connecting the said rods and serving to interpose as a stop against movement of the valve away from said opening in the plate beyond a predetermined position. 110

17. Temperature - controlled apparatus comprising a bellows thermostat, a supporting device fixedly connected with one end of the thermostat, a partition member having a valve opening mounted beyond the opposite free end of the bellows thermostat, a stem projecting from the free end of the thermo- 120

stat, a valve adjustably connected to the stem, and a means for insuring a predetermined and constant travel of the valve from closed to full open position independently of the relative position to which the valve may be adjusted with respect to the stem.
